US0D1070318S

(12) **United States Design Patent** (10) **Patent No.:** **US D1,070,318 S**
(45) **Date of Patent:** **** Apr. 15, 2025**

(54) **SHOE**

(71) Applicant: **NIKE, Inc.**, Beaverton, OR (US)

(72) Inventor: **Jordyn N. Klumpp**, Beaverton, OR (US)

(73) Assignee: **NIKE, Inc.**, Beaverton, OR (US)

(**) Term: **15 Years**

(21) Appl. No.: **29/908,484**

(22) Filed: **Jan. 12, 2024**

(51) LOC (15) Cl. **02-04**

(52) U.S. Cl.

USPC **D2/960**; D2/954

(58) Field of Classification Search

USPC D2/902, 906–908, 946–949, 951–955,

D2/958, 960, 962

CPC A43B 13/20; A43B 5/02

See application file for complete search history.

(57) **CLAIM**

The ornamental design for a shoe as shown and described.

DESCRIPTION

FIG. 1 is a bottom rear perspective view of a shoe showing my new design;

FIG. 2 is a bottom view thereof;

FIG. 3 is a bottom front perspective view thereof;

FIG. 4 is a bottom rear perspective view of a shoe showing a second embodiment of my new design;

FIG. 5 is a bottom view thereof; and,

FIG. 6 is a bottom front perspective view thereof.

The broken lines depicting the remainder of the shoe form no part of the claimed design.

1 Claim, 6 Drawing Sheets
